FOUR CYLINDER LOCOMOTIVE

James C. Maris, Glenolden, Pa.

Application March 27, 1937, Serial No. 133,407

5 Claims. (Cl. 105—82)

This invention relates generally to a driving spring system for four cylinder locomotives, especially of the single rigid frame type, employing forward and rear sets of cylinders and drivers.

5 In four cylinder locomotives of the above type as heretofore proposed, the forward and rear sets of drivers have been maintained entirely independently of each other in their spring suspension systems with consequent possibility of unequal stress and strain distribution in the single frame. Inasmuch as the whole frame is necessarily subjected to power impulses at its forward and intermediate points, it is desirable to minimize the possibility of any supplementary adverse 10 conditions.

It is an object of my invention to provide an improved driving spring system that is comparatively inexpensive in construction, operation and maintenance and is relatively simple and compact as well as being effective in bringing the forward and rear sets of drivers of a four cylinder type of locomotive into such cooperation that will insure a more uniform load distribution within the single frame while at the same time 25 maintaining maximum flexibility of the multiple sets of drivers, all notwithstanding the interposition of the rear cylinder structure between the forward and rear sets of drivers.

Another object is to provide improved means 30 for supporting the driving springs whereby a relatively large diameter boiler may be employed without having the spring arrangement interfere therewith. It is well known that certain prior driving spring arrangements, when used on 35 locomotives having large diameter boilers, result in breaking the boiler lagging and in some instances of unduly wearing or contacting the boiler shell. Another object is to permit certain of the foregoing desirable results to be accomplished 40 most effectively by the provision of improved means for supporting the usual loop spring hangers on the spring clips at each end of the main driving springs, and it is a still further object to permit maximum lateral swinging of 45 the hangers with respect to the springs without imposing undue stress at the point of connection at the bottom of the hanger, this being especially desirable where it is attempted to obtain maximum flexibility in a four cylinder locomotive 50 of the single frame type, although it will of course be understood that various features disclosed herein may be utilized in connection with other types of locomotives. This particular subject matter constitutes the disclosure of 55 a co-pending divisional application.

Other objects and advantages will be more apparent to those skilled in the art from the following description of the accompanying drawings in which:

Fig. 1 is a side elevation of the forward portion of a four cylinder locomotive of the single frame type; 5

Fig. 1a is a side elevation of the rear portion of the locomotive and constitutes a continuation of Fig. 1; 10

Fig. 2 is a transverse section taken on the line 2—2 of Fig. 1;

Fig. 3 is a horizontal section taken on the line 3—3 of Fig. 2;

Fig. 4 is a transverse section taken on the line 15 4—4 of Fig. 1;

Fig. 5 is a transverse section taken on the line 5—5 of Fig. 1 through one of the main driving springs and its spring saddle;

Fig. 6 is a transverse section taken on the line 20 6—6 of Fig. 1;

Fig. 7 is a vertical longitudinal section taken on the line 7—7 of Fig. 6 showing my improved spring hanger arrangement;

Fig. 8 is an enlarged fragmentary view of the 25 upper end of the spring hanger showing its supporting attachment to the outer end of the main driving spring.

In the particular embodiment of the invention, such as is disclosed herein merely for the 30 purpose of illustrating one specific form among possible others that the invention might take in practice, I have shown in Figs. 1 and 1a a locomotive of the general type described in the McCarroll Patent 1,622,917 in which a single, preferably integrally cast, frame 1 has forward and rear sets of cylinders 2 and 3 for driving respectively forward and rear sets of drivers 4 and 5 through usual piston rods 6 and 7 and usual connecting and driving rods not shown. A boiler 35 8 is suitably supported upon usual cylinder saddles of the forward and rear cylinder structures while leading and trailing trucks 9 and 10 are also preferably employed to insure proper support of the frame and boiler. Each of the driving boxes 11, 12, 13 and 14, suitably guided in pedestals 15, is provided with identical spring saddles 16 comprising upward extensions of the driving boxes. Each of the driving springs 17, 18, 19 and 20 is identically supported upon the 40 hangers 16, and hence the description of one such support will suffice for all. As seen in the transverse section of Fig. 5, the spring 17 has a spring band 21 provided with laterally projecting trunnions 22 and 23 supported in a suitable arcuate 45 50 55

seat 24, Fig. 1. The inner trunnion 22 is provided with a lip 25 so that the inner saddle element 26 suitably reinforced at 27 resists either inward or outer lateral forces. As a result of this improved trunnion type spring band, it is seen that the driving spring 17 is adapted to be appreciably lower than would be the case if the lower portion of the spring band was seated directly on top of the usual spring saddle.

10 The forward end of spring 17 has a spring hanger 28a, Figs. 6 and 8, provided at its closed end with a recess 28 for receiving a cylindrical projection 29 of a hardened semi-spherical wearing member 30. This member is supported on a suitable spring clip 31 having a seat 32 of larger radius than the semi-spherical surface of member 30. A portion 33 depends into aligned openings formed in the outer ends of the spring leaves. The lower end of the spring hanger 28a is connected by a radial steel roller or thimble 34 journalled upon a cross-connecting pin 35. A spring support 36 rests upon the roller 34 while a spring 37 is interposed between support 36 and an under portion of the frame 1.

25 Spring hangers 38 and 39 are constructed similar to hangers 28a but an equalizing beam 40 pivoted as at 41 to frame 1, is supported on the radial rollers corresponding to 34. The spring hangers 42, one on each side of the frame 1 as shown in Fig. 2, are cross-connected by transverse equalizing beams 43 pivotally connected at each of their ends 44 to suitable lugs 45 which are supported upon pins connecting the lower ends of the hangers. Pins 46 and lugs 45 correspond generally to the radial roller 34 and pin 35 of the other links.

40 The driving springs 19 and 20 for the rear set of drivers 5 together with their spring hangers and intermediate equalizing beam are identical to the corresponding elements of the forward drivers and hence further detailed description need not be given except to point out that the rearmost hanger 48 is suitably connected to a usual spring equalizing system of the trailer truck 10 through suitable equalizing beams 49 and links 50. However, the front spring hanger 51 together with cross-connecting equalizing beams are identical in every respect with hangers 42 and beams 43 including the connections therewith.

55 Notwithstanding that the rear cylinder structure 3 is interposed between these two spring systems, yet I propose bringing the same into cooperative relation by utilizing the rear cylinder structure broadly as a means of pivotally supporting a pair of equalizing beams 52 which are pivotally supported at 53 to lugs 54 depending from the intermediate portion 55 of the rear cylinder structure as shown in Fig. 4. The ends 60 of these equalizing beams are each seated in eyes 56, Fig. 2, of vertical links 57 which in turn are pivotally supported at 58 to the cross beams 43. As a result of this arrangement, it is seen that the driving spring rigging for the forward and rear sets of drivers insures complete cooperation between the two systems with minimum possibility of undesirable forces or conditions arising within the single integral main frame 1 with its cylinder structures 2 and 3 connected thereto at longitudinally spaced points thereof.

70 It is also seen that my improved construction permits maximum lateral flexibility consistent with maximum stability and ruggedness. The spring hangers with their removable hardened

ball members 30 and the radial sleeves 34 insure the utmost in flexibility without undue wear of the parts, while my improved trunnion type spring bands 21 in association with the upwardly extending saddles 16 insures that the main driving springs will be at a minimum height so as to permit use of a large diameter boiler but without in any way restricting the flexibility of the spring rigging systems or the cooperative action between the same through the instrumentality of the equalizing beams 52 supported beneath the rear cylinder structure 3.

75 It will of course be understood that various changes in details of construction and arrangement of parts may be made by those skilled in the art without departing from the spirit of the invention as set forth in the appended claims.

I claim:

1. In combination, a locomotive having a single rigid frame with forward and rear cylinder structures and sets of drivers driven respectively from said cylinder structures, driving spring systems, one of which is located between said forward and rear cylinder structures and the other of which is located rearwardly of said rear cylinder structure, and equalizing means connecting said spring systems.

2. In combination, a locomotive having a single rigid frame with forward and rear cylinder structures and sets of drivers driven respectively from said cylinder structures, driving spring systems one of which is located between said forward and rear cylinder structures and the other of which is located rearwardly of said rear cylinder structure, and equalizing means pivotally supported by and beneath said rear cylinder structure for interconnecting said respective spring systems.

3. In combination, a locomotive having a single rigid frame with forward and rear cylinder structures and sets of drivers, main driving spring systems having springs on each side of the frame, said spring systems being respectively for the forward and rear sets of drivers, the rearmost springs on opposite sides of the forward system being connected by a cross-member and the forward springs of the rear system also being connected by a cross-member, and longitudinal equalizing means pivotally connected to said frame and to said cross-members.

4. In combination, a locomotive having a single rigid frame with forward and rear cylinder structures and sets of drivers, main driving spring systems having spring riggings extending along each side of the frame, said spring systems being respectively for the forward and rear sets of drivers, the rearmost springs on opposite sides of the forward system being connected by a cross-member and the forward springs of the rear system also being connected by a cross-member, and a plurality of longitudinal equalizing beams pivotally supported by said frame and extending forwardly of said rear cylinder structure for connection to the cross-member of the forward spring system and extending rearwardly of the rear cylinder structure for connection to the cross-member of the rear spring system.

5. The combination set forth in claim 4 further characterized by the provision of means for supporting said pair of longitudinal equalizing beams by said rear cylinder structure beneath the same.
